UNITED STATES PATENT OFFICE

173,267

ICE-CREAM CONFECTION

Peter Kokoris, Venice, Calif.

Application April 9, 1953, Serial No. 24,590

Term of patent 14 years

(Cl. D82—2)

To all whom it may concern:

Be it known that I, Peter Kokoris, a citizen of the United States, residing at Venice, California, have invented a new, original, and ornamental Design for an Ice-Cream Confection, of which the following is a specification, reference being had to the accompanying drawing, forming a part hereof.

Figure 1 is a top perspective view of an ice-cream confection showing my new design, and

Figure 2 is a bottom plan view thereof.

I claim:

The ornamental design for an ice-cream confection, substantially as shown.
